MINER'S SAFETY ACETYLENE LAMP

William Henry Dargue, Newcastle-upon-Tyne,
EnglandApplication May 5, 1933, Serial No. 669,511, and
in Great Britain May 12, 1932

6 Claims. (Cl. 240—18)

This invention relates to miners' safety acetylene lamps, and its primary object is to provide an improved construction wherein the flow of water to the carbide chamber is controlled by the pressure of gas within the carbide chamber acting in opposition to the pressure resulting from the effective head of water. A further object of the invention is to maintain a constant effective head of water until the greater part of the water has been used, thereby ensuring a uniform pressure of gas at the burner during the whole or the greater part of the period during which the lamp is in use. Another object of my invention is to regulate the flame of the burner to enable the lamp to be adjusted for testing for inflammable gas in a mine, and a further object is to relieve automatically excess gas pressure in the carbide chamber in the event of the water valve and the gas regulating valve both being turned off at the same time.

With these and other objects in view, as will appear as the description proceeds, the invention consists in the novel features of construction and the combinations and arrangements of parts hereinafter fully described and pointed out in the appended claims.

In the accompanying drawing which forms part of this specification,

Figure 1 is a central vertical section of a lamp in accordance with my invention;

Figure 2 is a plan thereof;

Figure 3 is a vertical section on the line 3—3 in Fig. 2; and

Figure 4 is a plan section on the line 4—4 in Fig. 1.

Referring more particularly to the specific form of my invention disclosed in the accompanying drawing, the numeral 10 designates the water chamber, 11 the carbide chamber, 12 the burner, 13 the glass cylinder surrounding the burner, 14 the chimney, 15 the safety gauze within the chimney, and 16 the handle whereby the lamp is carried and suspended.

The carbide chamber 11 comprises a cylinder 64 of sheet brass soldered to a ring 65 which forms the mouth of said chamber. At the bottom, the carbide chamber is closed by a recessed cap 57, the flange 66 of which is bent over to enclose the lower edge of the cylinder 64 and soldered thereto.

The metal cap 17, which is riveted to the in-turned upper edge of the chimney 14, is lined with asbestos 18 to insulate the pin 19 by which the handle 16 is attached to the cap and minimize the transmission of heat to the handle. The lower edge of the chimney 14 and of the safety

gauze 15 are attached to the perforated gallery 20 as usual, and the glass cylinder 13 is mounted between the gallery and a metal ring 21 around the burner 12, packing rings 22 for the purpose of making gastight joints being inserted between the cylinder 13 and the gallery, between the cylinder and the ring 21, and between the ring 21 and the flanged ring 23 which supports it. The ring 23 is screwed in a flanged base ring 24 which is screwed onto the outside of the ring 65 forming the mouth of the carbide chamber. The base ring 24 is attached by rods 25 to the gallery 20 as usual, said rods clamping the glass cylinder 13 and the ring 21 in position.

The water chamber 10 comprises the upper portion of a hollow column 67 of sheet brass projecting upwards from the carbide chamber 10 behind the chimney 14, and is separated from the carbide chamber 11 by a partition 26. A polished reflecting surface 27 is provided on the face of the column 67 behind the glass 13. The water chamber is filled through an aperture 28 in its top 29 normally closed by an airtight screw cap 30.

The flow of water from the chamber 10 to the chamber 11 is regulated by a device comprising a tube 31 extending through the water chamber into the carbide chamber, said tube communicating with the water chamber only through an aperture 32 near its lower end. A depending flange 33 extends below said aperture to prevent the passage of air or gas into the water chamber 10. The lower end of the tube 31 is closed by a screw cap 34 provided with a hollow stem 40, and its upper end is closed by a screw cap 35 in which is an air hole 36 through which the tube 31 is always open to the atmosphere.

Within the tube 31 is provided a valve comprising a cap 37 attached to a spindle 38 which is threaded at its upper end and passes through a threaded aperture in the cap 35 at the top of the tube beyond which it is fitted with a finger piece 39 whereby it can be rotated to raise and lower the cap. The cap 37 coats with the hollow stem 40 in the lower end of the tube and has a wire 41 which enters said stem to ensure a drip feed and provide means whereby its bore can be cleared of obstruction.

It will be seen that, if the spindle 38 is screwed down to cause the cap 37 to close the hollow stem 40, no water can pass from the tube 31 into the carbide chamber 11. When however the cap is raised off the top of the stem, the water in the tube 31 rises inside the cap above the top of the stem and passes down the stem into the

carbide chamber decomposing the carbide therein and generating acetylene gas, the flow continuing until the pressure of gas generated in the chamber 11 overcomes the pressure of the head 5 of water tending to cause the flow. When the latter condition occurs, the water in the stem 40 and cap 37 is forced back by the gas, and further flow of water is stopped until the gas pressure falls below the water pressure, the flow of 10 water to the chamber 11 being thus automatically cut off when the quantity of gas generated exceeds the consumption, and resuming again when the gas pressure falls.

An air pipe 42 is provided in the top 29 of the 15 water chamber, said pipe extending down into the chamber 10 as shown in Fig. 3. The object of this air pipe is to assure a uniform head of water in the tube 31, and the operation is as follows:— The chamber 10 is completely filled with water 20 through the aperture 28 which is then hermetically sealed by the cap 30. The water passes through the aperture 32 into the tube 31 and rises in said tube and also in the air pipe 42 to the level of the top of the chamber 10. As both the 25 tube 31 and the pipe 42 are open to the atmosphere, they form in effect the two upstanding members of a U-pipe, and fall of water level in one member instantly results in an equal fall in the other member. As the water drips out of the 30 tube 31 through the hollow stem 40, the level of water in the tube 31 falls and there is a corresponding fall in the air pipe 42 until said water level reaches that of the bottom of the pipe 42. Subsequently, any diminution of the water level 35 below the bottom of the pipe 42 allows air to pass from the air tube 42 into the water chamber 10, the water thereby displaced passing through the aperture 32 into the tube 31 and maintaining the head of water in said tube at the level of the bottom of the air pipe 42 and so keeping the 40 water pressure uniform in said tube, said water pressure being equivalent to the height of the bottom of the air pipe 42 above the top of the hollow stem 40. This constant water level is 45 maintained until the water level in the chamber 10 falls below the bottom of the air pipe 42 after which the water pressure gradually falls until the water level falls below the level of the aperture 32. If desired, the air pipe 42 can alternatively 50 be provided in the cap 30.

The burner 12 is mounted in a boss 46 in the centre of a flanged cover 47 screwed into the ring 65 forming the mouth of the carbide chamber 11, a packing ring 48 being interposed between the flange of said cover and the rim of the ring 65 to make a tight joint. The burner communicates with a depending tube 49 carried by the cover 47. A felt or like pad 50 is mounted around the tube 49 immediately below the cover 47 to dry and purify the acetylene gas which, after passing through said pad, passes into the tube 49 by orifices 51.

The supply of gas to the burner 12 is controlled by a needle valve 52 coacting with a valve seat 53 65 within the tube 49, the spindle 54 of said valve extending through a threaded aperture in the cap 55 of a stuffing box 56 in the recessed bottom cap 57 of the chamber 11 beyond which it is provided with a handle 58 whereby it can be rotated 70 to raise and lower the needle valve onto and from its seat.

To relieve excessive gas pressure generated in the carbide chamber 11 in the event of the water valve 37 and the gas regulating valve being both 75 turned off at the same time, I provide a relief

tube 43 (Fig. 3) opening out of the top of the chamber and extending up through a tube 44 depending into the water chamber 10 and carried by an air-tight screw cap 45 closing an aperture in the top 29 of the water chamber. The top of the tube 43 is above the top of the water chamber, and the tube 44 extends almost to the partition 26 forming the bottom of the chamber 10. Excess pressure gas in the carbide chamber will force down the water in the tube and will escape 85 into the water chamber 10.

To charge the chamber 11 with carbide, its ring 65 is unscrewed from the base ring 24 and its cover 47 is removed. Any suitable known locking means are fitted to prevent unauthorized 90 detachment of the carbide chamber from the base ring.

59 is a frictional igniting device operated by a spindle 60 which is a gas-tight fit in a sleeve 62 which passes through the metal ring 21. The spindle has a square end with which a square tube 63 fitted with a head 61 can be engaged as shown in Figs. 2 and 4 so that rotation of said head rotates the spindle 60 and the igniting device 59. The tube 63 and head 61 are removed from the 100 square end of the spindle 60 as shown in Fig. 4 when the carbide chamber 11 is to be unscrewed from the base ring 24.

By my invention I provide an improved miner's 105 acetylene safety lamp which can be readily adjusted for testing for gas and will be found very convenient and accurate for that purpose. To adapt my lamp for testing for gas, it is only necessary to reduce the flame of the burner 12 to a suitable degree by means of the needle valve 52. 110 My improved lamp is of strong construction and will stand the shocks incidental to mining work. As the water supply to the carbide chamber is automatically regulated and controlled, the lamp requires no more attention after the valve 37 is 115 turned on. The pressure of gas in the carbide chamber is substantially uniform, but means are provided for relieving any abnormal accumulation of pressure in the carbide chamber which may arise should the needle valve 52 be closed at 120 the same time as the valve 37.

While I have illustrated and described what I 125 now consider to be the preferred embodiment of my invention, it will nevertheless be understood that various changes or modifications of a more or less minor character may be made in the construction without departing from the spirit of my invention, or the scope of the subjoined claims. For example, my improved lamp may be 130 of any required size, and may, if desired, be designed as a fixture.

What I claim and desire to secure by Letters Patent is:—

1. A miner's safety acetylene lamp comprising 135 a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within 140 said tube, a water inlet near the bottom of said tube, a depending flange over said water inlet, and means for maintaining a constant effective head of water in said tube until the greater part 145 of the water in the water chamber has been used, 150

- comprising an air pipe depending from the top of the sealed water chamber.
2. A miner's safety acetylene lamp comprising a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within said tube, a water inlet near the bottom of said tube, a depending flange over said water inlet, means for maintaining a constant effective head of water in said tube until the greater part of the water in the water chamber has been used, comprising an air pipe depending from the top of the sealed water chamber and means for regulating the flame of the burner.
3. A miner's safety acetylene lamp comprising a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within said tube, a water inlet near the bottom of said tube, a depending flange over said water inlet, means for maintaining a constant effective head of water in said tube until the greater part of the water in the water chamber has been used, comprising an air pipe depending from the top of the sealed water chamber and means for regulating the flame of the burner, comprising a valve seat at the bottom of the burner, a needle valve coacting with said valve seat and extending through the carbide chamber, an operating device below said chamber for adjusting said valve.
4. A miner's safety acetylene lamp comprising a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within said tube, a water inlet near the bottom of said tube, a depending flange over said water inlet, means for maintaining a constant effective head of water in said tube until the greater part of the water in the water chamber has been used, comprising an air pipe depending from the top of the sealed water chamber, means for regulating the flame of the burner, comprising a valve seat at the bottom of the burner, a needle valve coacting with said valve seat and extending through the carbide chamber, an operating device below said chamber for adjusting said valve, 140
- vice below said chamber for adjusting said valve, and means for automatically relieving excess gas pressure in the carbide chamber.
5. A miner's safety acetylene lamp comprising a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within said tube, a water inlet near the bottom of said tube, a depending flange over said water inlet, means for maintaining a constant effective head of water in said tube until the greater part of the water in the water chamber has been used, comprising an air pipe depending from the top of the sealed water chamber, means for regulating the flame of the burner, comprising a valve seat at the bottom of the burner, a needle valve coacting with said valve seat and extending through the carbide chamber, an operating device below said chamber for adjusting said valve, and means for automatically relieving excess gas pressure in the carbide chamber, comprising an upstanding tube opening out of the top of the carbide chamber and extending up through the water chamber, and a depending tube within the water chamber over said upstanding tube.
6. A miner's safety acetylene lamp comprising a carbide chamber, a burner mounted thereon, a sealed water chamber above said carbide chamber, a transparent casing surrounding said burner, a chimney above said casing, a safety gauze within said chimney, said transparent casing, chimney and gauze being supported in gas-tight connection by the carbide chamber, a depending tube in said water chamber extending into the carbide chamber, an air inlet at the upper end of said tube, an adjustable valve within said tube, a water inlet near the bottom of said tube, a depending flange over said water inlet, means for maintaining a constant effective head of water in said tube until the greater part of the water in the water chamber has been used, comprising an air pipe depending from the top of the sealed water chamber, means for regulating the flame of the burner, comprising a valve seat at the bottom of the burner, a needle valve coacting with said valve seat and extending through the carbide chamber, an operating device below said chamber for adjusting said valve, 125
- means for automatically relieving excess gas pressure in the carbide chamber, comprising an upstanding tube opening out of the top of the carbide chamber and extending up through the water chamber, and a depending tube within the water chamber over said upstanding tube, a frictional igniting device adjacent to said burner, and means for operating said device from the exterior of the transparent casing surrounding the burner.

WILLIAM HENRY DARGUE.
